UNITED STATES PATENT OFFICE.

JOSEPH LANE WRIGHT, OF WASHINGTON, DISTRICT OF COLUMBIA, ASSIGNEE, BY
MESNE ASSIGNMENTS, TO FREDERICK C. STEVENS, OF ALFICA, NEW YORK.

TELEPHONE-EXCHANGE SYSTEM.

1,134,306.

Specification of Letters Patent.

Patented Apr. 6, 1915.

Application filed May 18, 1908, Serial No. 817,450. Renewed December 9, 1912. Serial No. 728,476.

To all whom it may concern:

Be it known that I, JOSEPH LANE WRIGHT, a citizen of the United States, residing at Washington, in the District of Columbia, have invented certain new and useful Improvements in Telephone-Exchange Systems, of which the following is a specification.

My invention relates to telephone exchange systems and especially to the type known in the art as full automatic, and the object of the invention is the provision of means for avoiding the use of ground connections for transmitting impulses.

Heretofore, to differentiate between the different classes of impulses such as the ones used for the vertical portion of the switch and those used for the rotary portion of the switch, it was necessary to directly ground the vertical side of the line and then send impulses thereover from the subscriber's sender, and in sending the rotary impulses, it was necessary to ground the opposite side of the line. To operate the releasing mechanism, it was necessary to ground both sides of the line. It is the object of my invention to do away with all of these ground connections as it is a well understood fact that a complete metallic line for all purposes is much superior to a ground circuit. It also does away with the complicated mechanism at the subscriber's station as I am enabled to use a simple make and break device.

In this invention for illustration I use the ordinary Strowger switches which are shown in the Keith and Erickson Patents No. 815,821, dated March 18, 1906, and No. 815,178, dated March 18, 1906, and it is therefore unnecessary to further describe these switches.

Specifically stated, my invention consists of two sets of relays, the first set controlled directly by a sensitive repeating relay for sending the vertical impulses to the switching mechanism, and the second set controlled jointly by the repeating relay and the first set of relays for sending rotary impulses to the switching mechanism. The joint action of these two sets of relays after the calling subscriber hangs up his receiver, restores the switching mechanism to its orig-

inal position. The first set of relays remains energized throughout the conversation, while the second set remains energized only during the transmission of the impulses. At the end of the conversation, both sets of relays become deenergized, the action of which sends in simultaneously a vertical and rotary impulse to the releasing mechanism. It will be seen by this combination of relays that I am able to transmit a set of impulses operating the switching mechanism and impulses for working the side switches of the switching mechanism, and impulses for effecting the release of the same by means of the small make and break device at the subscriber's station.

My invention is illustrated in the accompanying drawings wherein—

Figure 1 shows a subscriber's station with a portion of the central office equipment. Fig. 2 shows an extension of the central office equipment consisting of the circuits of the switching mechanism.

Referring now to Fig. 1, the subscriber's station A is equipped with apparatus usual in common battery installations consisting of the transmitter T, receiver R, hook H, ringers Q, condenser C, and in addition a push button P consisting of the normally closed contact springs φ and φ' . This push button takes the place and acts as the sending device for the subscriber in making a call.

To the line wires 1 and 2 bridged battery is supplied through the relay S and retardation coil S'. The relay S when energized controls the relay S' which in turn controls the relay S". The relay S also upon rapid making and breaking of its contacts controls the circuits of the relays S1, S2 and S3 in order. With this combination I am able to transmit impulses over the vertical or number 3 side of the talking circuit, or over the rotary or number 4 side of the talking circuit, and also to send simultaneous impulses over both wires 3 and 4, the operation of which will be described in detail later on.

Referring now to Fig. 2, the switching mechanism is of the well known Strowger type with a few changes which will be pointed out. The vertical and rotary relays

S⁷ and S⁸ which control the vertical and rotary magnets O and O' remain the same. The private relay D controlling the side switches remains unchanged. In place of the back release relays, which in the Strowger system are tied to the trunk wires 5 and 6, I have substituted the retardation coil S¹⁰ and the relay S⁹. This relay S⁹ upon becoming energized when the called subscriber answers, attracts its armature and disconnects the ringing relay. The relay G is connected in place of the ringing relay K and controls it when energized. In the branch of the ringing relay K which ordinarily is connected directly to battery, I have inserted an interrupting machine J, which alternately opens and closes the circuit of the ringing relay K when the relay G is energized. I have also added the two foot springs z and z' controlled by the spindle Z for the purpose of disconnecting the relay G when the switch assumes its normal position in case the called party does not answer.

The operation of my system is as follows: Referring now to Fig. 1, the subscriber at station A desiring to make a call removes his receiver, closing the circuit of the relay S at central. The relay S becoming energized attracts its armature and closes the circuit of the relay S⁴ by the following path: battery B, 20, 19, s', s, 11, S⁴, to ground. The relay S⁴ becoming energized closes the contacts s¹¹ and s¹² thereby completing the circuit of the relay S⁶. The relay S⁵ becoming active connects ground to one terminal of the relay S² by the following path: ground, s¹⁴, s¹³, 13, to winding of S². The relay S being sensitive is readily responsive to any makes and breaks of the subscriber's line such as caused by his sending device when making a call. The relays S⁴ and S⁵ are made sluggish and when once energized will keep their armatures attracted while impulses are being sent in and the contacts s and s' of the relay S are making and breaking. The relay S⁴ is affected slightly by these makes and breaks, but the relay S⁵ being controlled by the relay S⁴ is not affected in the slightest. As soon as the subscriber has removed his receiver and starts to send in his number with his sending device, which I have for simplicity represented by the push button P, the relay S becomes responsive. This relay, making and breaking the contacts s' and s², closes the circuit of the relay S² by the following path: battery B, 20, 19, s', s², 18, S², 13, s¹³, s¹⁴ to ground. The relay S² becoming energized closes the circuit of the relay S³ which in turn closes the circuit of the relay S⁶. These three relays S², S³ and S⁶ remain energized or active so long as a set of impulses are being sent in affecting the relay S. It will

of course follow that the relay S² is slightly affected by the making and breaking of the contacts s' and s², and the relay S³ is less affected by these makes and breaks, while the relay S⁶ is not affected in the least.

Having described how these various relays are operated and controlled, I will now show how the various impulses are transmitted to the connector switch shown in Fig. 2.

The subscriber, after removing his receiver, proceeds to send in the first digit of the desired number by manipulating the push button P. The relay S, being responsive to these impulses, makes and breaks its contacts corresponding to the number of impulses sent in. The set of relays S², S³ and S⁶ become energized while the relays S⁴ and S⁵ became energized the instant the subscriber removed his receiver. The relay S in Fig. 1 repeats the impulses to the relay S⁷, Fig. 2, by the following path: battery B, 20, 19, s', s², s⁵⁰, s¹⁸, 23, 3, S⁷ to ground. The relay S⁷ operating, closes the circuit of the vertical magnet O by the following path: ground, s²⁵, s²³, 30, d, d', 31, F, 40, O, 41, 45 to battery B. The operation of the magnet O causes the spindle Z carrying the wipers w and w' to step up vertically bringing the wipers opposite a row of contacts corresponding to the number of impulses sent. After this set of impulses has been sent in, there is a momentary or prolonged closure of the line and the relay S remains energized, opening the contacts s' and s², disconnecting the set of relays S², S³ and S⁶. The deenergizing of this set of relays which drop back in one, two, three order, allows an impulse to be sent in over the rotary side of the trunk to the relay S⁸ by the following path: battery B, 20, 19, s⁴, s³, 14, s⁸, s⁷, 15, s²⁰, s¹⁹, 24, 4, S⁸ to ground. The relay S⁸ becoming energized, closes the circuit of the private relay D as in the ordinary Strowger system, which in turn causes the side switches F, F', F² and F³ to move one point. This movement of the side switches disconnects the vertical magnet O and in its place connects the rotary magnet O'. It also connects the test relay X to the tip wiper w by the following path: 46, F³, 32, d², d³, 34, 35, X, 36, 33, 45, to battery B. The subscriber now sending in the second set of impulses of the desired number, operates the relay S which, as before, closes the set of relays S², S³ and S⁶ and transmits the impulses over the vertical side of the trunk operating the relay S⁷ which now in turn operates the rotary magnet O' causing the spindle Z to rotate and carry the wipers opposite the contacts leading to the desired line. After this second set of impulses has been sent in, the relays S², S³, and S⁶ become disconnected and an impulse is sent in over the rotary side of the trunk

operating the relay S^8 which upon closing the circuit of the private magnet D causes the side switches F , F' , F^2 , and F^3 to make another step disconnecting the rotary magnet O' and in its place connecting the relay G . During this momentary impulse over the rotary side of the trunk, the test relay X is connected to the tip wiper w by the closing of the contacts d^2 and d^3 . If the 5 called line was busy, this relay would become energized and close the circuit of the release magnet X' and restore the switch to its normal position. While I have shown the test relay X as applied to the sleeve 10 wiper w , I am not limited to this specific connection for releasing the switch in case the called line is busy. It is obvious that the restoration of the switch under such 15 conditions may be secured in a number of other ways, as for instance by means of a third wiper and coöperating stationary contacts arranged in the manner shown in the Keith and Erickson Patents Nos. 815,321 and 20 815,176, previously referred to. Taking it 25 for granted that the called line is idle, the called subscriber sends in a third set of impulses, or a single impulse will answer the purpose, affecting the relay G which, becoming energized, locks itself through the 30 contacts g and g' . This relay remaining energized closes the circuit of the ringing relay K in series with the interrupting machine J . This relay becoming energized and deenergized connects and disconnects 35 generator current to the called subscriber's line, ringing his bell alternately. The called subscriber upon removing his receiver completes the circuit of the relay S^9 while the relay K is momentarily deenergized. 40 This happens when the pen or wiper of the interrupting machine is resting on the insulated portion. The relay S^9 becoming energized opens the contacts s^{26} and s^{27} , disconnecting the relay G which in turn cuts 45 off the ringing relay K , thus preventing ringing current from flowing over the line after the called subscriber has answered.

At the end of the conversation, the calling subscriber hanging up his receiver de- 50 energizes the relay S and its armature falling back disconnects the relay S^4 , but before the relay S^5 can become deenergized on account of its being sluggish, the circuits of the relays S^2 , S^3 and S^6 are closed through 55 the contacts s' and s^2 . Now by the time this second set of relays has become energized, the relay S^5 has become deenergized and the relays S^2 , S^3 and S^6 begin to drop off in one, two, three order, the relay S^2 first and the 60 relay S^6 last. During this interval an impulse is placed on number 3 side of the trunk by the following path: battery B , 28, s^{10} , s^9 , 22, s^{17} , s^{18} , 23 to wire 3. A similar impulse is placed on number 4 side of the

trunk through the contacts s^{16} and s^{15} . This 65 impulse being placed simultaneously on both trunk wires, operates the relays S^7 and S^8 which in turn closes the circuit of the test relay X by the following path: ground, s^{21} , s^{22} , 35, X , 36, 33, 45 to battery B . This 70 test relay closes the circuit of the release magnet X' which restores the switch and all its parts to the normal or idle position. If the called subscriber has not answered his telephone, the relay S^9 would not have become energized and the relay G would remain in a locked position. The foot springs z and z' are provided to meet this contingency so that even if the called party does not answer, the circuit of the relay G is 75 opened when the switch is restored.

It will be seen that I have formed two sets or groups of relays, one set of which is controlled directly by a single relay and the other set by the joint action of the single 85 relay and the first set. This combination allows me to differentiate between the various sets of impulses sent in over the subscriber's line to operate the switching mechanism and to restore the same to normal position after the calling party has hung up his receiver.

Having thus described my invention, what I claim and desire to secure by Letters Patent is:

1. In a telephone exchange system, the combination with a plurality of subscribers' stations having impulse senders and a central station provided with an extension circuit, of switching mechanism at the central 100 station in the extension circuit controlling the continuity of the subscribers' lines as between subscribers, impulse transmitting means for the rotary side of the extension, impulse transmitting means for the vertical side of the extension, said impulse transmitting means for the vertical side of the extension controlling both the rotary and vertical impulses; releasing mechanism for 105 said switching mechanism, and means for 110 controlling the same.

2. In a telephone exchange system, the combination with a switching circuit, switching mechanism at the terminus thereof, impulse transmitting means for the vertical 115 side of the circuit, impulse transmitting means for the rotary side of the circuit, controlling means for both the vertical and rotary sides of the circuit, said controlling means acting in conjunction with the vertical impulse transmitting means to control the rotary impulse transmitting means, releasing mechanism, and means comprising the vertical and the rotary impulse transmitting means and controlling means for 120 operating said releasing mechanism.

3. In a telephone exchange system, the combination with a switching circuit, switch-

1. In a telephone exchange system, the combination at the terminus thereof, impulse transmitting means for the vertical side of the circuit, controlling means for both the vertical and rotary sides of the circuit, said controlling means acting in conjunction with the vertical impulse transmitting means to control the rotary impulse transmitting means, a plurality of subscribers' stations having impulse senders, means located thereat for controlling the impulse transmitting means, releasing mechanism at the central station, and means comprising the vertical and the rotary transmitting means and the controlling means for operating said releasing mechanism when the subscriber has hung up his receiver.
2. In a telephone exchange system, the combination with a plurality of subscribers' lines and stations having impulse senders and a central station containing an extension circuit for each line, and switching mechanism at the terminus thereof, of a set of relays for sending the vertical impulses to the switching mechanism, a set of relays for sending the rotary impulses for the switching mechanism, and a controlling relay acting in conjunction with the vertical relay through its back contact to control the rotary relays.
3. In a telephone exchange system, the combination with a plurality of subscribers' lines and stations having impulse senders and a central station containing an extension circuit for each line and switching mechanism at the terminus thereof, of a set of sluggish relays controlling the vertical impulses to the switching mechanism, a quick acting relay in the set for operating said sluggish relays, a set of relays for transmitting the rotary impulses to the switching mechanism, said quick acting relay of the vertical set controlling in combination with the sluggish relays the action of the relays for the rotary impulses, releasing mechanism, and means comprising the vertical and rotary relays and the quick acting relay for operating said releasing mechanism when the subscriber hangs up his receiver.
4. In a telephone exchange system, the combination with a plurality of subscribers' lines and stations and a central station containing an extension circuit for each line and switching mechanism, a set of relays at the central station, means at the subscriber's station for controlling the relays at the central station whereby vertical impulses are sent over the circuit to the switching mechanism, another set of relays at the central station acting upon the release of the means at the subscriber's station to send a rotary impulse to the switching mechanism, releasing mechanism, and means for controlling the releasing mechanism.
5. In a telephone exchange system, the combination with a plurality of subscribers' stations provided with impulse sending devices, and a central station containing a connective circuit and switching mechanism, the latter provided with a movable connecting part having vertical and rotary movements, of a plurality of sets of impulse transmitting relays, a sensitive repeating relay directly controlling one of said sets for sending the vertical impulses to the switching mechanism and another set being controlled jointly by the repeating relay and the first mentioned set of relays for sending rotary impulses to the switching mechanism.
6. In a telephone exchange system, a plurality of subscribers' stations provided with impulse senders, a central station provided with an automatic switch having vertical and rotary movements, a sensitive repeating relay at said central station, two sets of transmitting relays arranged to control the automatic switch, the first set of said relays remaining energized throughout conversation, the second set remaining energized only during the transmission of the impulses from the repeating relay.
7. In a telephone exchange system, subscribers' lines provided with impulse sending devices, a central station having an automatic switching mechanism, a repeating relay, two independent sets of relays controlled by said repeating relay for operating said automatic switch, and means actuated by the deenergization of both sets of relays to effect the disconnection and restoration of said switch to normal.
8. In a telephone exchange system, subscribers' lines provided with impulse sending devices, a central station provided with an automatic switch for interconnecting said lines, said switch having vertical and rotary movements, two independent sets of impulse transmitting relays arranged to transmit vertical and rotary impulses to the automatic switch thereby effecting a talking connection, said sets of relays operating at the end of the conversation to cause a simultaneous vertical and rotary impulse to be sent to the releasing mechanism for effecting a disconnection of the talking circuit and a restoration of the parts to their normal condition.
9. In a telephone exchange system, a plurality of substations, a plurality of automatic connective switches and circuits for interconnecting the same, means for originating and directing impulses to the switches to effect desired connections, test circuits associated with certain of said switches and individually closed in response to a special test impulse, automatic ringing means also associated with said switches and comprising a ringing relay having a circuit par-

tially closed as a result of the aforesaid test impulse and adapted to be completed by a subsequent impulse especially directed thereto, and a locking circuit for said ringing relay opened when the called subscriber answers.

In testimony whereof I have signed my

name to this specification in the presence of two subscribing witnesses.
